UNITED STATES PATENT OFFICE

122,148

DESIGN FOR A FURNACE BODY

Max C. Richardson, Portland, Oreg., assignor to
Iron Fireman Manufacturing Company, Port-
land, Oreg.

Application June 10, 1939, Serial No. 85,445

Term of patent 14 years

To all whom it may concern:

Be it known that I, Max C. Richardson, a citizen of the United States, residing at Portland, county of Multnomah, State of Oregon, have invented a new, original, and ornamental Design for Furnace Bodies, of which the following is a specification, reference being had to the accompanying drawing, forming part thereof.

The figure is a perspective view of a furnace body, showing my new design.

The other side of the article is substantially like the side shown and the rear is substantially plain.

I claim:

The ornamental design for a furnace body, as shown and described.

MAX C. RICHARDSON.
